BACKGROUND OF THE INVENTION

Field of the Invention (Technical Field)

The present invention relates to keepsake objects (preferably memorial keepsake objects) and methods of manufacture of same.

BRIEF SUMMARY OF THE INVENTION

Embodiments of the present invention comprise molded keepsake articles of jewelry comprising a shape, a molded cavity fillable with cremated remains, hair and/or personal effects of a deceased or living person or animal, an adhesive to seal the fillable cavity, and a jewelry finding (e.g., a bail) disposed over the adhesive to cover it. In one embodiment, the articles of jewelry further comprise a birthstone color for the birthday of said deceased or living person or animal. One preferred embodiment is a geometric and/or teardrop shape. The articles of jewelry are preferably manufactured of stone, plastic, fired glass, metals, etc. When the keepsake articles of jewelry comprise a teardrop shape, the cavity is preferably located in the narrow portion of the teardrop shape.

A different embodiment of the present invention comprises a kit for making a keepsake wherein a cavity is provided open for a consumer or funeral professional to fill in the cavity with cremated ashes, hair and/or personal effects of a deceased person or animal, adhesive for applying after filling said open cavity, a jewelry finding for covering the adhesive, and user instructions.

Embodiments of the invention further comprise a method of manufacturing a keepsake article of jewelry comprising obtaining cremains, hair and/or personal effects of a deceased or living person or animal, casting an article of jewelry comprising a cavity, filling the cavity with the cremains, hair and/or personal effects of a deceased or living

person or animal, sealing the cavity with an adhesive or cement, and placing a finding on the adhesive or cement to cover it.

Objects, advantages and novel features, and further scope of applicability of the present invention will be set forth in part in the detailed description to follow, taken in conjunction with the accompanying drawings, and in part will become apparent to those skilled in the art upon examination of the following, or may be learned by practice of the invention. The objects and advantages of the invention may be realized and attained by means of the instrumentalities and combinations particularly pointed out in the appended claims.

**15 BRIEF DESCRIPTION OF THE SEVERAL
VIEWS OF THE DRAWINGS**

The accompanying drawings, which are incorporated into and form a part of the specification, illustrate one or more embodiments of the present invention and, together with the description, serve to explain the principles of the invention. The drawings are only for the purpose of illustrating one or more preferred embodiments of the invention and are not to be construed as limiting the invention. In the drawings:

FIG. 1 is a perspective view of a mold for simultaneously making one or more copies of a memorial keepsake of the present invention;

FIG. 2 shows an embodiment of a fired glass memorial keepsake with and without a screw attaching a finding to adhesive covering a filled cavity; and

FIG. 3 is a display comprising several memorial keepsakes.

**35 DETAILED DESCRIPTION OF THE
INVENTION**

This invention relates to a keepsake article of jewelry or a similar item, including but not limited to a pendant, pin, tie tack, lapel pin, token (for pocket), earring(s), other jewelry and the like. The invention preferably comprises a teardrop shaped item, but can be of any shape. The item can be drilled or has a cavity resulting from molding or pre-drilling. The cavity in the item preferably is filled with "cremains" (cremated ashes), hair and/or personal effects of a deceased or living person or animal. The cavity is preferably then sealed with an adhesive and preferably, and alternatively, a jewelry finding (e.g. a bail) is disposed over the sealed area. The term "adhesive" as used throughout the specification and claims is intended to include adhesive, glue, cement, moldable and curing materials, epoxies, and the like. The terms "keepsake" and "memorial keepsake" may be interchangeably used throughout the specification.

Materials such as stone, plastic, glass, or metals are preferably drilled or molded to form a cavity, which cavity is then filled with ashes or other substances. The holes or cavities are preferably sealed by using adhesive or cement after placing the cremated ashes or any other memorable substances therein. In an alternative embodiment, the substance (e.g. cremains) is mixed with an adhesive or sealing substance which then cures or dries to seal the cavity. If a single cavity is created, it is preferably located in the narrow portion of the keepsake.

As shown in FIG. 1, one or more memorial keepsakes can be molded at once via mold 10 with one or more hollows 11, and each memorial keepsake preferably comprises at least one cavity formed during the molding process by posts 12.

The resulting preferred teardrop shape is disclosed in FIG. 1 via the resulting shape from the mold illustrated.

An embodiment of the invention is the fabrication of memorial keepsakes comprising the steps of; obtaining 5 cremains, hair and/or personal effects of a deceased or living person or animal; casting or molding or providing an article of jewelry comprising a cavity; filling the cavity with the cremains, hair and/or personal effects of a deceased or living person or animal; sealing the cavity with an adhesive or cement; and disposing a finding over the adhesive or cement to cover the cavity.

The invention is further directed to a kit for making the memorial keepsake, which would comprise the keepsake body (preferably with the drilled hole although the user could do the molding and/or cavity formation e.g. drilling), any jewelry finding (if the keepsake memorial is jewelry or an accessory) and, alternatively, the adhesive or cement. The kit would also include instructions for filling the keepsake with the cremains or other items, and sealing it or mixing it 15 with the adhesive/cement.

In an alternative embodiment, the memorial keepsake may have the birthstone color for the birthday of the person being memorialized or remembered. The memorial keepsake can be for human or animal remains or mementos of a living or deceased person or animal, or for other items that the buyer may want to keep as a memory.

Referring to FIG. 2, the drawing shows the cavity (filled with the item) covered by a jewelry finding. Optionally, the finding is further secured with, for example, a screw inserted into the adhesive or cement. In FIG. 2, a cavity filled with cremains is covered by a finding with a top bail that is screwed in place and covers the adhesive.

Referring to FIG. 3, in a different embodiment, the memorial keepsake is affixed to, or hung in a display (e.g. a point of sale display).

INDUSTRIAL APPLICABILITY

The invention is further illustrated by the following non-limiting examples.

Example 1

A fired glass teardrop shaped memorial keepsake article comprising a fillable cavity was fabricated by casting fired glass in the mold of FIG. 1. After it cooled, the cavity on the article was then filled with cremains of a deceased person and sealed with an adhesive. A jewelry bail was placed over the adhesive to cover it. The color of the glass was the birthstone color of the deceased person.

The preceding example can be repeated with similar success by substituting the generically or specifically described components and/or parameters of this invention for those used in the preceding examples.

Although the invention has been described in detail with particular reference to these preferred embodiments, other embodiments can achieve the same results. Variations and modifications of the present invention will be obvious to those skilled in the art and it is intended to cover in the appended claims all such modifications and equivalents. The entire disclosures of all references, applications, patents, and publications cited above are hereby incorporated by reference.

What is claimed is:

1. A keepsake article of jewelry comprising:
a necklace pendant comprising a front and a back, wherein said necklace pendant is configured so that said back faces a user when worn and said front is for display;
a cavity positioned and configured such that it is not visible when said article of jewelry is worn;
said cavity fillable with cremated remains, hair and/or personal effects of a person or animal;
a jewelry finding disposed on said back of said necklace pendant;
an adhesive or cement and said finding to seal said cavity and to enclose the cremated remains, hair and/or personal effects of the person or animal therein;
said jewelry finding comprising a bail;
said jewelry finding disposed to cover said cavity and said adhesive or cement;
a screw; and
said finding secured with said screw inserted into said adhesive or cement.
2. The keepsake article of jewelry of claim 1 wherein said necklace pendant comprises a birthstone color for a birthday of the person or animal.
3. The keepsake article of jewelry of claim 1 wherein said necklace pendant comprises a teardrop shape.
4. The keepsake article of jewelry of claim 1 wherein said necklace pendant is made of stone.
5. The keepsake article of jewelry of claim 1 wherein said necklace pendant is made of plastic.
6. The keepsake article of jewelry of claim 1 wherein said necklace pendant is made of glass.
7. The keepsake article of jewelry of claim 1 wherein said finding is made of metal.
8. The keepsake article of jewelry of claim 1 wherein said cavity is located in a narrow portion of said necklace pendant.
9. The keepsake article of jewelry of claim 1 further comprising a memento of a person or animal, in addition to the cremated remains, hair and/or personal effects of the person or animal disposed in said cavity.
10. The keepsake article of jewelry of claim 1 wherein said necklace pendant is a geometric shape.
11. The keepsake article of jewelry of claim 1 wherein said necklace pendant is a molded material.
12. The keepsake article of jewelry of claim 11 wherein said cavity is molded in said necklace pendant.
13. The keepsake article of jewelry of claim 1 wherein said cavity is drilled.
14. A kit for making a keepsake comprising the keepsake article of jewelry of claim 1, wherein said cavity provides an opening for a consumer to fill in said cavity with the cremated ashes, hair and/or personal effects of a person or animal; and
user instructions.
15. A method of manufacturing a keepsake article of jewelry comprising:
obtaining cremains, hair and/or personal effects of a person or animal;
providing a necklace pendant comprising a front and a back, wherein the necklace pendant is configured so that the back faces a user when worn and the front is for display;
providing a cavity that is not visible when the necklace pendant is worn by the user;
filling the cavity with the cremains, hair and/or personal effects of the person or animal;
providing an adhesive or cement;

disposing a finding comprising a bail on the back of the necklace pendant;
sealing the cavity with the adhesive or cement and the finding to enclose the cremains, hair and/or personal effects of the person or animal; 5
covering the cavity and the adhesive or cement with the finding;
providing a screw; and
securing the finding with the screw inserted into the adhesive or cement. 10
